(57) **CLAIM**

The ornamental design for a human body detector, as shown and described.

DESCRIPTION

1. Human body detector

1.1 : Front

1.2 : Back

1.3 : Left

1.4 : Right

1.5 : Top

1.6 : Bottom

1.7 : Perspective

1.8 : Perspective

1.9 : Reference view in position of use

1.10 : Reference view in position of use

1 Claim, 10 Drawing Sheets
